UNITED STATES PATENT OFFICE

2,611,261

BUILDING BLOCK CONSTRUCTION

Edwin L. Preston, River Forest, Ill.

Application March 16, 1948, Serial No. 15,161

4 Claims. (Cl. 72—42)

1

This invention relates to a new and improved building block construction.

One of the principal objects of this invention is the provision of a building block which in itself possesses all the characteristics of a recognized standard building wall.

An important object of this invention is to provide a building block which simulates a brick building wall.

Another object of this invention is to provide a concrete building block with a brick veneer.

Another object of this invention is the provision of a building block having an inner wall capable of receiving and holding an inside plaster.

A further object of this invention is to provide a cementitious building block with a perforated metallic plate removably attached to the inner side of the block in such a manner that the plate is locked in fixed position after the application of an inner wall plaster.

A still further object of this invention is the construction of a building block with means for carrying individual insulation packs.

Another object of the invention is to provide a metal reinforced concrete building block.

Another and still further object of the invention is the provision of an expanded metal reinforced concrete building block with the expanded metal arranged and constructed to receive and grip inner wall plaster.

Still another object is to provide a building block with means to uniformly space adjacent blocks to insure an even mortaring between all the blocks in a building wall.

Another object is to provide a building block capable of use as a conduit for heating or cooling systems.

Another and further object is the provision of means in a building block to receive electrical, water, or gas conduits flush with the inner surface of the block to provide a smooth surface for plaster or other inner wall coverings to be applied directly therover.

Other and further important objects will become apparent from the disclosures in the following specification and accompanying drawings.

In the drawings:

Fig. 1 is a perspective view of a partial building wall incorporating the building blocks of this invention.

Fig. 2 is a perspective view of the outside corner block employed in the wall in Fig. 1.

Fig. 3 is a perspective view of a half-block used in this construction.

Fig. 4 is a perspective view of a regular block

2

as employed in the wall of Fig. 1 without metal back plates.

Fig. 5 is a rear elevational view of a portion of the wall of Fig. 1.

Fig. 6 is a sectional view taken on the line 6—6 of Fig. 1.

Fig. 7 is a top plan view of an inside corner of a modified form of block.

Fig. 8 is a top plan view of another modified form of building block.

Fig. 9 is a sectional view taken on the line 9—9 of Fig. 8.

Fig. 10 is an enlarged sectional detail of the rear of a metal backed block showing the interlocking after applying inner wall plaster.

As shown in the drawings:

The reference numeral 10 indicates a generally rectangular building block as shown in Fig. 4. The block 10 consists of a cementitious front 11

20 with rearwardly extending integral sides or ends 12 and 13. The word cementitious shall be construed to mean any material suitable for building blocks such as ordinary limestone cement, plastics, or any material in the form of a mortar which when set produces a hard stony surface. A partition 14 is integral with the front 11 and is positioned parallel to and intermediate the ends 12 and 13.

A brick slab 15 is molded integrally to the front of the block 10 as a veneer at a time when the block is formed. The brick slab pieces are offset in a manner corresponding to regularly laid brick. The wall as shown in Fig. 1 does not appear to be made of large blocks because of the offsetting of the brick slabs 15. The slabs do not cover the entire front of each block as shown by the blank spaces 16 and 17. After a wall is completed with blocks of this type, additional brick slab pieces 18 are laid with mortar in adjacent aligned spaces to conceal the joints of the large blocks.

40 It will be noted that the blank spaces are recessed in the concrete so that sufficient mortar may be applied to attach a brick slab of an adjoining block. As shown in Fig. 4, the brick slabs 18 extend fully across the top and bottom. In order to meet all conditions and mate with all adjoining blocks the veneered brick may be applied to the regular block as shown in Fig. 1 at 19. Similar blank recessed spaces are provided in the corner and half blocks to be described. The block

50 20 is designated an outside corner as it is adaptable for use on an outside corner of a building in deference to an inside corner block 21 as shown in Fig. 6 which is used as an inside corner. An outside corner is designated on the wall of Fig. 1

by the letter A and an inside corner is designated by the letter B. The block 20 is a full length block and differs from block 10 only by its end 22 which is finished with a brick veneer. As shown in Fig. 1 the corner blocks are all full length blocks which interlock. The first tier of wall blocks has the corner end 22 facing one of the adjoining walls. Similarly every other tier of blocks has the end 22 facing the same wall. In the second tier the corner block 20 is turned over and reversed so that the veneered end 22 is facing the other of the adjoining walls and the veneered front 23 of the block also faces outwardly.

As shown in Fig. 3, a half block 24 is provided with two adjacent brick veneered surfaces 25 and 26. The use of a half block is depicted in Fig. 1. The half block is positioned adjacent door or window frames to compensate for the offsetting of blocks in the vertical tiers. A half block 24 is shown abutting a door frame 27 which is set slightly back from the front surface of the building wall. Thus the brick slab covered end 26 is necessary to complete the finished brick appearance. The outside corner blocks 20 having the brick veneered end join with the half blocks to complete finished openings for doors or windows. The corner block alternates with the half blocks so the vertical walled opening is lined with a fully veneered surface.

The blocks are all provided with spacing strips or projections such as those shown at 12a and 13a on the block 10 in Fig. 4. The end 28 without a brick covering of the outside corner block 20 has a similar spacing strip 28a. The half block 24 has one of its non-brick veneered ends 29 equipped with a strip 29a corresponding to the strips 12a, 13a, and 28a. As shown in Fig. 1 the several strip projections abut each other and maintain correct and uniform spacing of the blocks in building a wall. In building with large blocks it is important and very difficult to properly space the blocks. With the projection strips 12a, 13a, 28a, and 29a in use as space guides the building blocks are easily maintained in uniform spacing and as a consequence the mortar is also of uniform thickness.

The building blocks are equipped with insulation pads directly in back of the front or outside walls of the block. In Fig. 4 the insulation pads are shown at 30 and 31. These insulation pads are relatively stiff packs and are slidable into position within opposed grooves 30a and 30b and 31a and 31b in the ends and partitions 12, 13, and 14. In the corner block 20 of Fig. 2 insulation packs 32 and 33 are positioned behind both the outer walls. The insulation package 32 is L-shaped and has one portion 32a back of the veneered end 22 and the other portion 32b back of the veneered front 23. Here also the stiff packs are held in grooves 32c, 32d, 33a, and 33b formed in the concrete walls of the block. Similarly in the half block of Fig. 3 a single insulation package 34 is L-shaped having leg portions 34a and 34b behind the brick-veneered faces 25 and 26. The outer ends of the insulation package are held in grooves 34c and 34d.

It is necessary to apply inner wall plaster to the combined backs of the blocks and thus the backs are designed to receive and grip plaster. In Fig. 4 the backs have been removed to show the recessed construction of the rearwardly extending ends of the sides and partitions 12, 13, and 14. The recessed or cut-out portions, as shown at 36 and 37 in the ends 12 and 13 respectively, are equipped with an inclined undercut as best shown

at 38 in Fig. 9. A similar undercut is shown at 39 in the recess 37. The block partition 14 is equipped with a double recess 40 which as shown in Fig. 3 includes opposed recesses 41 and 42, each having an inclined undercut 43 and 44. The recesses 36 and 41 and their respective undercuts 38 and 43 combine to receive the side edges 45 of a perforated metal back plate 46. The edges 45 form a right angle with the main back portion of the plate 46. When the blocks in a wall are all laid the removable back plates are applied and press fitted on the backs of the blocks as shown in Fig. 1. As best shown in Fig. 10 the plaster 47 flows through the plate perforations 48 and fills the space 49 between the plate side 45 and the inclined undercut 38. Upon setting and hardening of the plaster the back plate is thoroughly locked and anchored to the building block 10 and thus the entire plaster wall is securely held in position.

Another advantage in the backs 46 being removable is the possibility of providing certain of the backs with electrical outlet boxes, switches, etc. which may be moved to any desired space on the wall.

The recess 40 in the partition 14 also includes a central passage 50 which may be used to receive conduit such as used for electricity, gas, or water. An electrical conduit 51 is shown mounted in the vertically disposed passage formed of the passages 50 in the partitions 14 and the passages 52 formed at the juncture of two blocks by the mortar spacing guides or strips 12a and 13a. With this block construction, electrical, gas, or water pipes or conduits may be positioned in the vertical slots formed in the walls prior to plastering. Plastering is then done directly over the back plates and the positioned conduits.

Heating, cooling, or any air conditioning passages or conduits are formed right in the building blocks. As shown in blocks of Figs. 4 and 6, vertical passages 53 and 54 are formed between the end wall 12 and the partition 14 and the partition 14 and the other end wall 13 respectively. The partition 14 is provided with a laterally extending passage or opening 55 so that air, whether it be hot or cold, may pass through the entire building wall. The use of the hole 55 in the partition permits the directing of air horizontally through the wall as well as vertically although the horizontal path is somewhat tortuous. Thus conditioned air whether it be hot or cold can and does travel both horizontally and vertically through a wall composed of building blocks of this invention. When the passages 55 are left open or uncovered a whole wall may be used as a heating panel as hot air delivered within any block will have communication with every other block and the heat therefore permeates the entire wall. If it is desired to form a particular passage preselected openings 55 may be closed by mortar when the blocks are being laid. When a special passage is routed through the wall of blocks the back of the end block or the backs of any of the blocks may be left free of inner wall plaster so that hot, cold, or any conditioned air may be discharged into or removed from the interior of the room. Such non-plaster covered block backs then are and act as registers. Even after certain of the openings 55 are closed for the forming of particular passages the remainder of the wall is not obstructed for the transmission of air which may be directed upwardly from the foundation of the building.

This opening 55 is very important to the successful functioning of the building block. When

properly used the openings act as built-in air conduits. Merely by closing off certain of the openings as discussed above air may be directed to or from any preselected area or spot. With wall type heating already accepted this feature of built-in wall conduits becomes increasingly important.

As shown in Fig. 7, a modified form of building block incorporates all the principles of the block just described, but employs a different back or inner wall. The back 56 is a material made of a mixture of concrete and such other constituents as slag, cinders, and/or sawdust which is in a plastic or fluid state when initially formed and is thus poured simultaneously with the remaining concrete portions of the block. When the block sets and hardens it is one integral piece. The mixture of other materials in the concrete makes the back somewhat porous to receive and grip plaster applied thereover and to easily receive and hold nails. Thus any type of inner wall may be attached to the inside of the blocks as shown in Fig. 7. The soft porous mixture of the back 56 of block 21 in Fig. 7 is formed with a central vertical conduit groove 57 and mortar guide ribs 58 and 59. As shown and described for the blocks of Figs. 2, 3, and 4, the joining of adjacent guide ribs forms additional conduit grooves.

In order that the brick slabs will be firmly held to the main block, they are knifed or slotted at frequent intervals on their backs as shown at 60 so that as concrete or other substance is forced into the grooves the brick slabs are locked to the block upon the setting of the concrete or other substance used.

Figs. 8 and 9 show another modified form of building block. An expanded metal core 61 provides reinforcement for the concrete front 62 and sides 63 and 64. The back 65 of the expanded metal core 61 is uncovered to present an inner wall plastering surface in the same manner as the perforated metal backs 46 of Fig. 4. The remainder of the block has all the other appointments possessed by the blocks of Figs. 4 and 7 such as the vertical groove 66 and the mortar spacing guides 67 and 68, which guides form grooves with adjacent blocks to continue the vertical groove from the block immediately below or above.

Insulation packs are applied to the block of Fig. 7 in the same manner as that shown for the blocks of Figs. 2, 3, and 4. However, in the block of Figs. 8 and 9 the insulation packs 66 and 67 are shown positioned and held between the front wall of the expanded metal and the inner side of the front wall of the block thus eliminating the necessity of formed grooves.

Numerous details of construction may be varied throughout a wide range without departing from the principles disclosed herein, and I therefore do not propose limiting the patent granted hereon otherwise than as necessitated by the appended claims.

What is claimed is:

1. In a generally rectangular building block having a front, sides, and rear comprising a cementitious front and sides, the rear ends of the

sides having an inclined undercut, and a metal plate constituting the rear of said block, said metal plate having means for removable attachment to the rear of said block, said metal plate being perforated to receive inner wall plaster, said means including forwardly extending flanges, said forwardly extending flanges overlying the inclined undercuts of the sides of the block, whereby by plaster applied to the perforated metal back wall fills the space between the inclined undercut and the metal plate flanges and the setting of the plaster locks the back wall in fixed position.

2. In a generally rectangular building block having a front, sides, and a partition parallel to and between the sides, the rear end of said sides having an inclined undercut, and the rear end of the partition having a pair of oppositely disposed inclined undercuts, each of which complements the inclined undercut of one of said sides.

3. In a generally rectangular building block having a front, sides, and a partition parallel to and between the sides, the rear end of said sides having an inclined undercut, the rear end of the partition having a pair of oppositely disposed inclined undercuts, each of which complements the inclined undercut of one of said sides, and said partition having a vertical groove formed between the oppositely disposed inclined undercuts whereby a conduit may be positioned in said vertical groove.

4. In a generally rectangular building block having a front, sides, and a partition parallel to and between the sides, the rear end of said sides having an inclined undercut, the rear end of the partition having a pair of oppositely disposed inclined undercuts, each of which complements the inclined undercut of one of said sides, said partition having a vertical groove formed between the oppositely disposed inclined undercuts whereby a conduit may be positioned in said vertical groove, and the outsides of said sides having vertically extending guide ribs whereby when several blocks are placed together adjacent guide ribs form another vertical groove and the vertical groove of the partition is continued upwardly uninterrupted.
